UNITED STATES PATENT OFFICE.

ANDREW J. SARUP, OF NORTH VANCOUVER, BRITISH COLUMBIA, CANADA, ASSIGNOR
TO ANNIE M. SARUP, OF NORTH VANCOUVER, CANADA.

SAFETY-HOOK.

1,398,654.

Specification of Letters Patent. Patented Nov. 29, 1921.

Application filed June 29, 1920. Serial No. 392,629.

To all whom it may concern:

Be it known that I, ANDREW J. SARUP, citizen of the Dominion of Canada, residing at North Vancouver, in the Province of 5 British Columbia, Canada, have invented certain new and useful Improvements in Safety-Hooks, of which the following is a specification.

This invention relates to a closed hook 10 or link for connecting wire ropes together or for connecting other devices to wire ropes, the object being to provide a closable hook, any pull imposed on which will tend to maintain the closure, and one that is free 15 from projections calculated to catch or entangle on obstructions when drawn through the bush.

The device is fully set forth in the following specification, reference being made 20 to the drawings by which it is accompanied, in which:

Figure 1 is a side elevation of the link with the closure in the open position.

Fig. 2 is a top plan view of the hook. Fig. 25 3 is a section, on an enlarged scale, of the end of the hook closure showing the latch.

In these drawings 2 represents the hook, the shank of which is bent round, as at 3, to oppose the point of the hook and leave a 30 space 4 for the introduction of the rope or sling which it may be desired to connect.

Pivottally mounted on a pin in the end of 35 3 is a closing member 5, the free end of which is beveled, as at 6, to fit a corresponding bevel on the point of the hook against which it abuts, and the contacting faces of hook and closure are tongued and grooved together to prevent lateral displacement.

The closing member 5 has a portion 7 40 which projects squarely across the link so formed, and is apertured to receive the link or eye splice of the wire rope to which it is permanently connected.

The member 5 is retained in the closed 45 position by a latch bolt 10 which is end-wise movable in a socket provided for it adjacent the inner edge of the free end of 5. The latch bolt 10 is limited in its outward movement by a pin 11 which is secured 50 in the bolt 10 and passes through an elongated slot 13 in the adjacent edge of the closing member 5 to slightly project and form a finger engagement, by which the latch bolt may be withdrawn against the 55 resistance of a spring 12 which normally

holds it at the outer limit of its movement. The outer end of the latch bolt 10 engages a shoulder 14 formed on the inner end of the tongue of the hook. The line to which the hook is relatively 60 permanently fastened, is connected at 7 to the inner end of the closing member 5, and tension on that line will thus tend to hold the point of that member closed on the hook point, in which closed position it is latched 65 by the bolt 10 engaging the inner end 14 of the tongue.

It forms, therefore, a safety hook retaining any rope or sling that may be introduced through the opening 4, and at the 70 same time it is free from any projection likely to catch or entangle in brush or roots when being drawn through the bush.

Having now particularly described my invention, I hereby declare that what I claim 75 as new and desire to be protected in by Letters Patent, is:

1. A safety hook, the shank of which is recurved toward the point of the hook, a member pivotally mounted in the recurved 80 end of the shank and adapted to close against the end of the hook and aline therewith, said member having a projection within the recurved shank to which a line is connected, the tension of which line tends 85 to hold the closing member in the closed position.

2. A safety hook, the shank of which is recurved toward the point of the hook, a member pivotally mounted in the recurved 90 end of the shank and adapted to close against the end of the hook and aline therewith, said member having a projection within the recurved shank to which a line is connected, the tension of which line tends to 95 hold the closing member in the closed position, the point of the hook being angularly beveled to form a stop for the corresponding beveled end of the closing member.

3. A safety hook, the shank of which is 100 recurved toward the point of the hook, a member pivotally mounted in the recurved end of the shank and adapted to close against the end of the hook and aline therewith, said member having a projection within the recurved shank to which a line is connected, the tension of which line tends to 105 hold the closing member in the closed position, the point of the hook being angularly beveled to form a stop for the correspond- 110

ing beveled end of the closing member, the beveled end of the hook having a tongue projecting from the mid-thickness of the hook, the point of the closing member having a corresponding groove to receive the tongue when the hook is closed.

4. A safety hook, the shank of which is recurved toward the point of the hook, a member pivotally mounted in the recurved 10 end of the shank and adapted to close against the end of the hook and aline therewith, said member having a projection within the recurved shank to which a line is connected, the tension of which line tends to 15 hold the closing member in the closed posi-

tion, the point of the hook being angularly beveled to form a stop for the corresponding beveled end of the closing member, the beveled end of the hook having a tongue projecting from the mid-thickness of the 20 hook, the point of the closing member having a corresponding groove to receive the tongue when the hook is closed, the closing member having an endwise movable latch to engage the inner end of the tongue of the 25 hook point and retain the closed member in the closed position.

In testimony whereof I affix my signature.

ANDREW J. SARUP.
